(57) **CLAIM**

The ornamental design for an automobile tire tread, as shown and described.

DESCRIPTION

FIG. 1 is a front perspective view of an automobile tire tread showing our new design;

FIG. 2 is a front view thereof, the rear, top plan and bottom plan views being identical thereto; and,

FIG. 3 is a right-side view thereof, the left-side view being identical thereto.

The broken lines are environmental only and form no part of the claimed design.
